HEATER

George L. Johnson, New York, N. Y., and William A. Hagerbaumer, Westfield, N. J., assignors to Socony-Vacuum Oil Company, Incorporated, a corporation of New York

Application April 4, 1946, Serial No 659,442

1 Claim. (Cl. 263—19)

1 This invention relates to apparatus for heating a granular solid to an elevated temperature.

The apparatus of this invention is adapted for use in processes for conducting a chemical reaction at high temperature by bringing fluid reactants into direct contact with a highly heated bed of granular solids. In processes such as the cracking of hydrocarbon fractions to produce large yields of ethylene at temperatures on the order of 1400 to 1600° F. it is highly desirable that the hydrocarbon charge be heated very rapidly in order to minimize undesirable secondary reactions. This is advantageously accomplished by contact with a hot granular solid and the apparatus of this invention provides means for heating a granular solid evenly and efficiently to a suitable high temperature to be later used for heating the hydrocarbon charge. According to the invention, a flame is directed against and impinges on a surface of the granular solid to be heated and the hot products of combustion are thereafter passed directly through a moving bed of granular solid in order to take full advantage of the heating capacity of the hot gases.

Essentially, the invention contemplates propagation of the flame on the surface of the granular solid to be heated in order to obtain efficient combustion but a portion of the granular solids is shielded from the direct flame and later used as an economizer section in the region where the combustion products are passed directly through the mass of solids.

The apparatus of this invention is well adapted to be used in a complete system utilizing two cycles of solid circulation, in the first of which, reactants are heated to a high temperature by contact with a hot solid and, in the second of which, the reaction products are quenched to a temperature below that at which reaction occurs by direct contact with a relatively cold solid. In the complete system described herein, the solid for quenching is cooled by contact with air which is thereafter used as preheated air for use in the burners of the heater to which the invention is primarily directed. A heater structure embodying the principles of this invention is shown, as a sectional view in side elevation, in the single figure of the annexed drawing wherein 10 represents a shell enclosing the heater. Granular solids to be heated are supplied through an inlet pipe 11 at the top of the vessel to pass downwardly through an upper and a lower heating zone as described hereinafter.

The upper heating zone is an annular passage defined by an inner louvered wall 12 and an outer

5 louvered wall 13, both depending from a transverse plate 14. The space within the inner louvered wall 12 constitutes a chamber for supply of hot gases of combustion to flow laterally through the annular bed of solids to a space about outer wall 13 from which the flue gas is discharged by outlet 15.

10 The thus heated granular solid passes downwardly and is deflected by member 16 to a second 15 annular heating zone similarly defined by an outer louvered wall 17 and an inner louvered wall 18, the space within wall 18 constituting, with the interior of member 16 and the interior of wall 12, a passage for conducting hot gases of 20 combustion from the lower to the upper heating zone.

25 It will be seen that the granular solid passing from the upper to the lower heating zone will appear as a circular bed having a face exposed 20 to a combustion chamber defined in part by said bed and in part by a refractory ring 19. Openings for introduction of fuel burners are provided by nipples 20 spaced around the combustion chamber.

30 25 The hot gases of combustion generated within the combustion chamber pass downwardly about the wall 17 and thence laterally through the annular bed to the interior of wall 18 from which they pass upwardly to move through the bed 30 in the upper heating zone as previously described.

35 The walls 17 and 18 are supported by a plate 21 having a plurality of granular solid discharge nipples 22 passing therethrough. The nipples 22 are spaced to obtain uniform withdrawal of solids 35 from all parts of the annular bed in the lower heating zone and thereby promote uniform flow throughout both heating zones. The heated solids collect in the conical bottom of shell 10 from which they are withdrawn by pipe 23 for any 40 desired use.

We claim:

45 In apparatus for heating a granular solid, a first inner louvered wall defining the lower section of a vertical flue, a first outer louvered wall defining an annular vertical heat transfer zone about said lower section of said flue, a second inner louvered wall defining the upper section of said flue, a second outer louvered wall defining an annular vertical heat transfer zone about 50 said upper section of said flue, means to pass an annular bed of granular solid material downward serially through said heat transfer zones, means defining a combustion zone open to a surface of said bed intermediate said sections of said flue, burners in said combustion zone directed

against said surface to generate a flame impinging on said surface, means to conduct hot products of combustion from said combustion zone to the outer face of said first outer louvered wall, and means to withdraw gases from about said second outer louvered wall.

GEORGE L. JOHNSON.
WILLIAM A. HAGERBAUMER.
